CLAIM

The ornamental design for a striped cabinet as shown and described.

DESCRIPTION

FIG. 1 is a perspective view of a striped cabinet, showing my new design;

FIG. 2 is another perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is a partial enlarged view of FIG. 1;

FIG. 9 is a partial enlarged view of FIG. 2; and,

FIG. 10 is a partial enlarged view of FIG. 2.

The broken lines in the figures and the dashed circles in the enlarged view are for the purposes of illustrating portions of the striped cabinet, which form no part of the claimed design.
